Moses B. Wright

United States Patent Office.

MOSES B. WRIGHT, OF MERIDEN, CONNECTICUT.

Letters Patent No. 65,851, dated June 18, 1867.

IMPROVEMENT IN LAMP-BURNERS.

The Schedule referred to in these Letters Patent and making part of the same.

TO ALL WHOM IT MAY CONCERN:

Be it known that I, MOSES B. WRIGHT, of Meriden, in the county of New Haven, and State of Connecticut, have invented certain improvements in Lamp-Burners, of which the following is a full, clear, and exact description, reference being had to the accompanying drawings, making part of this specification, in which—

Figure 1 is a central vertical section through my improved lamp-burner.

Figure 2 is a horizontal section on the line $z-z$ of fig. 1.

Figure 3 is a detail to be referred to.

To prevent the too rapid formation of gaseous vapors within the lamp, caused by the ordinary wick-tube imparting its heat to the contents of the lamp, is the object of my invention, which consists in two wick-tubes, one placed above the other, the upper one being of a larger diameter than the lower, which is of the ordinary size, corresponding to the wick to be used therein, and my invention consists in certain other improvements, which will be mentioned hereafter.

To enable others skilled in the art to understand and use my invention, I will proceed to describe the manner in which I have carried it out.

In the said drawings A is a burner of a lamp for burning the products of crude petroleum or coal oil. Within the base a of this burner is soldered or otherwise secured a wick-tube, b , (see fig. 1,) which is of a diameter just sufficient to receive the wick c . The top of this tube b extends to about the top of the cap d , which is not perforated and is fitted snugly to the upper part of the base a of the burner. The base a is not perforated, but solid, so as completely to prevent the escape of any volatilized oil from the lamp, except what passes up through the wick in tube b . A wick-tube, e , of a diameter somewhat larger than that b , is secured to the cap at a point, f , one-eighth of an inch or less above the top of the tube b , but not surrounding it, and extends upward to any desired height. Extending around the outside of the upper wick-tube e is a circular flange, g , to which is secured one end of a chain, to the other end of which is fastened the extinguisher B . The flange g is provided with a slit, h , and the lower edge of the extinguisher B is turned up slightly, in order that it may be hung upon the flange, by which construction the noise ordinarily attending the carrying of the lamp from place to place is avoided. Instead of securing the chain to a flange, g , a hook, projection, or other device, forming a part of or attached to the tube e , may be employed, if desired.

As the diameter of the interior of the upper tube is larger than that of the wick, the latter fits quite loosely when placed therein, and when the wick is lighted the heat of this tube is not communicated to the fluid contained in the wick, and consequently the fluid in the lamp is prevented from being volatilized too rapidly, and a clear, steady, smokeless light is produced at all times. The wick-tubes b e may either be flat or round, and may be used in burners constructed for use with or without a chimney.

I distinctly disclaim the form and arrangement described in the patent of Daniel L. Pickard, dated January 30, 1866.

Claim.

What I claim as my invention, and desire to obtain by Letters Patent, is—

A lamp-burner provided with two wick-tubes b e , one of which, e , is placed above and not surrounding the other, b , and which communicates with a closed chamber below, substantially in the manner and for the purpose set forth.

MOSES B. WRIGHT.
